UNITED STATES PATENT OFFICE.

CARL W. HODGSON, OF DENVER, COLORADO.

TUNNELING-MACHINE.

1,353,908.

Specification of Letters Patent. Patented Sept. 28, 1920.

Application filed July 19, 1918. Serial No. 245,753.

To all whom it may concern:

Be it known that I, CARL W. HODGSON, a citizen of the United States, residing at Denver, in the county of Denver and State 5 of Colorado, have invented certain new and useful Improvements in Tunneling-Machines, of which the following is a specification.

This invention relates to improvements in 10 tunneling machines particularly adapted, though not necessarily limited in its use, for tunneling through rock, and one of the objects of this invention is to provide an improved machine of this character having 15 a series of cutters adapted to rotate independently and also for simultaneous bodily rotation, the cutters being so disposed with respect to each other as to provide a right angle cutting surface so that the diameter 20 of the opening or tunnel as it is cut will be uniform, and the advancement of the machine during the cutting period will not be interfered with.

The cutters are so arranged and positioned that the outer edges thereof will be 25 protected and the entire active surfaces of the cutters will be worn down evenly.

A further object of this invention is to 30 provide an improved machine of this character which will disintegrate the rock from the breast of the tunnel in such a manner that no ribs will be formed to interfere with the operation of the machine and the formation of projections usually caused by the 35 rock breaking away unevenly, will be avoided.

A further object is to provide an improved machine of this character which will operate speedily and which can be easily 40 controlled.

A further object is to provide improved means for removing the muck or broken particles of stone from the tunnel.

To the attainment of these ends and the 45 accomplishment of other new and useful objects as will appear, the invention consists in the features of novelty in substantially the construction, combination and arrangement of the several parts hereinafter more 50 fully described and claimed and shown in the accompanying drawings illustrating this invention and in which:

Figure 1 is a view partly in side elevation and partly in section of an improved ma-

chine of this character constructed in accordance with the principles of this invention.

Fig. 2 is a view as taken on line 2—2, Fig. 1.

Fig. 3 is a view as taken on line 3—3, Fig. 1.

Fig. 4 is a view as taken on line 4—4, Fig. 1.

Fig. 5 is a diagrammatic view as taken on line 5—5, Fig. 1, showing the relative positions of the cutters with respect to each other.

Fig. 6 is a detail view as taken on line 6—6, Fig. 1.

Fig. 7 is a view taken on line 7—7, Fig. 1, with parts omitted.

Fig. 8 is an enlarged detail view partly in elevation and partly in section of one series of cutters.

Fig. 9 is a detail sectional view of a guiding means for the operating cables of the cutters.

Figs. 10 and 11 are detail sectional views of two of the cutter heads showing the staggered relation of the cutters with respect to each other.

Fig. 12 is a perspective view of one of the cutters.

Fig. 13 is a detail sectional view on line 13—13, Fig. 6.

Referring more particularly to the drawings, the numeral 15 designates a suitable support of any desired size and configuration, and which is itself supported preferably by means of rollers 16 mounted in bearings 17, and which, in turn, move in suitable guides 18 connected with the support 15. These rollers 16 engage the wall of the tunnel and are adapted to be adjusted toward and away from the support 15 in any suitable manner, such as by means of an adjusting wheel 19 and a suitable connection 20 with the roller and which connection may be in the form of a threaded shaft, so that when the wheel 19 is operated, the rollers 16 may be adjusted so that they will contact with the wall of the tunnel and hold the support 15 in the desired position.

This support 15 may be of any desired length to extend transversely of the tunnel and has superposed thereon another support or table 21 which may be of any desired or suitable construction, and disposed between

the supports 15—21 are roller bearings 23—24 movable in suitable guideways so as to shift the support 21 with respect to the support 15. This shifting movement may be accomplished in any suitable manner, such as by means of a rack 25 preferably connected with the support 15 and a worm 26 which is mounted in suitable bearings and is connected with the support 20, and 10 this worm may be operated in any suitable manner such as by means of a gear 27 connected with the worm, which gear meshes with another gear 28 on a shaft 29 mounted in suitable bearings, and to which shaft 29 15 is connected an operating handle or wheel 30, so that when the handle 30 is actuated to revolve the shaft 29, the worm gear 26 will be operated and will cause the support 21 to be shifted with respect to the support 20. 15. The rack 25 and the bearings 23—24 are preferably constructed on an arc so that when the support 21 is shifted, the front or cutting end of the apparatus may be turned with respect to the support 15 to properly 20 position the cutters, as will be readily understood.

Mounted in suitable bearings 31 on the support 21, is a central operating shaft 32 which is preferably hollow and projects for 30 a considerable distance beyond the front of the supports 15—21. Secured to the shaft to rotate therewith and preferably located adjacent the forward end of the shaft is an element 33 preferably in the form of a disk, 35 which is of a diameter somewhat smaller than the diameter of the tunnel to be cut, and this disk 33, together with another disk or element 34 located in the rear thereof, and which is also secured to the shaft 32 40 to rotate therewith, form supports for the cutters to be hereinafter described.

The disk 33 is preferably provided with a reduced laterally projecting portion 35 having peripheral teeth 36 thereon and with 45 which teeth a gear 37 meshes, and by means of which the disk 33 and shaft 32, together with the cutters supported thereby, are given rotary movement. The gear 37 receives its motion from a shaft 38 to which it is secured, and the shaft 38 is journaled in suitable supporting bearings 39, the latter being preferably located upon the support 21. A motor 40 is provided upon the support 21 for operating the shaft 38 through the medium of a train of gears 41—42—43—44—45.

A protecting casing 46 is provided for the gear 37 and also the periphery of the disk or element 33, the latter being provided 60 about its periphery with a worm 47 with which a gear 48 meshes. Interposed between the worm 47 and the casing 46 are a series of rollers 49 upon which the element or disk 33 rests, and the casing 46 is provided with a cut-away portion 50 (see par-

ticularly Figs. 1 and 13) so as to permit the gear 48 to project thereinto and mesh with the worm 47, so that when the disk or element 33 is rotated, a slow rotation will be given to the gear 48. This gear 48 in 70 turn is connected with rollers 51, through the medium of intermeshing gears 52—53, and, as the rollers 51 engage and rest upon the tunnel wall, they not only support the disk or element 33, but serve as a means 75 whereby the machine will be advanced into the tunnel, the support 15 with its superstructure being advanced with the element 33 through the medium of suitable connecting rods 54 arranged preferably between 80 the casing 46 and the support 15.

The casing 46 has also connected with it rollers 55 which may be of a construction similar to rollers 51, and these rollers 55 also contact with the wall of the tunnel and 85 serve as a means to guide the structure. The casing 46 is preferably of a sectional construction as shown more clearly in Fig. 6. If desired, a housing 56 may be provided for the space between the disks or elements 90 34, to protect the parts and to prevent particles of stone or rock from becoming wedged between the parts.

A plurality of tubular elements 57 are supported by the elements 33—34, and the 95 forward ends of these tubular elements project for some distance in front of the disk or element 33, and these elements 57 form supports for the cutters, and as the construction of all of the cutters is the same, 100 the specific description of one will apply equally as well to them all, reference being had more particularly to Figs. 8 to 11.

Each of the cutters preferably comprises a plurality of separate cutter heads 58 105 which are provided with cutter seats 59 opening through their peripheries, the bottom of the seat being preferably angular in cross section so as to receive the angular extremity 60 of the cutter 61. The heads are 110 preferably of a width substantially equal to the width of the extremity 60 of the cutter, so that the cutter can be placed in its seat through the side of the cutter head. When all of the cutters are assembled on the shaft 115 62, which latter is preferably angular in cross section, and which cutters are inserted in corresponding apertures in each of the cutter heads so that the sides of adjacent cutter heads will abut, and as the cutters 120 are arranged in staggered relation, it will be manifest that the cutters will be held against lateral displacement with respect to the heads. In the end cutter head 63, the openings 64, which receive the angular extremities 60 of the cutters, do not extend entirely through the head, so that the cutters will not move out of their seats. The shaft 62 has connected with it a pulley 65 which is located 125 preferably between the respective 130

series of cutters, and the shaft is journaled in suitable bearings 66 in a yoke 67, the latter being connected with the extremity of a tubular member 57. The respective extremities of the tubular members 57 are deflected or arranged in such a manner that when all of the cutters are assembled and placed in position, the ends of the adjacent cutters will overlap as shown more clearly in the diagram in Fig. 5. This arrangement is provided in order to prevent the formation of ribs on the breast of the tunnel, as the cutters are all so arranged that portions of the cutters overlap the ends of the other cutters, with the result that the cutters will cut to a uniform depth in the breast of the tunnel.

By the arrangement of the cutters, the difficulty heretofore experienced by the cutters forming the breast of the tunnel at a substantially right angle to the wall or periphery of the tunnel has been avoided, which is desirable because heretofore such a formation has resulted in the gradual decreasing of the diameter of the bore of the tunnel, with the result that such gradual decreasing of the tunnel interferes with the operation of the tools and the advancement of the machine in the tunnel as the work progresses.

It will also be noted that the cutters are not only given a bodily rotation about the shaft 32 as an axis, but they are also given an independent rotation with respect to their support, and the cutters are given such a speed of rotation that they will overcome the vibration of the particles which hold the rock together, and disintegrate the particles, thereby overcoming the objectional vibration between the cutters and parts which is always manifested in a machine of the type employing reciprocating drills.

The cutters are given an independent rotation with respect to the shaft 62 in any desired or suitable manner, but preferably as before mentioned, by means of the pulley 65, over which an endless band or cable 68 passes, and this cable extends through the tubular member 57, suitable pulleys 69-70 being provided to guide the cables, and the cables also pass over a drum 71 which is preferably provided with a series of grooves to receive the respective cables, and the drum is mounted loosely upon the shaft 32, preferably between the element 33 and the support 21. Rotation is imparted to the drum 71 from a motor 72 which is also mounted upon the support 21, and is connected with the drum preferably by means of a chain 73 which passes over a sprocket 74 secured to the motor shaft, and a sprocket 75 connected with the drum 71.

Thus it will be manifest that the speed of rotation of the cutters with respect to their support may be controlled at will by the

control of the motor 72 in any ordinary or well-known manner, not necessary to illustrate.

If desired, a spray pipe 76 may be provided and this pipe is located in advance of the element 33, preferably behind the cutters and receives its supply from a suitable source through the medium of a pipe 77 which is connected with one end of the hollow shaft 32, and the spray pipes 76 may be of any desired number and connected with the end of the shaft 32 to rotate therewith. A shield 78 may also be provided and located preferably between the disk or element 33 and the spray pipes 76, and serves as a means for confining the dust at the forward end of the machine.

If desired, and in order to dispense with some of the tubular elements 57, a similar tubular element 79 (see Fig. 9) may be provided having its extremity branched or forked to form the tubular extensions 80-81, each of the extensions supporting one of the yokes 67, and so arranged that the endless bands 68 will pass therethrough, without interfering with each other.

The mined material or muck, as it is dislodged, is taken up and carried away so as to permit the machine to advance. This may be accomplished in any suitable manner, but preferably by means of scoops 82, any number of which may be provided, but in the present drawings two of such scoops are illustrated.

These scoops may be of any desired size, and are preferably supported by the disk or element 33, which latter is provided with openings 83 therethrough, and adjacent which openings the discharge ends 84 of the scoops are located. The outer ends of the scoops may be of any desired configuration suitable for the purpose. Thus it will be seen that as the material is cut away and as the disk or element 33 is rotated, the scoops 82 will rotate therewith and during such rotation the broken down material will be taken up by the scoops and will be discharged through the openings 83 in the element or disk 33, and delivered upon a suitable conveyer 85. This conveyer may be of any desired construction, but is preferably of the endless belt type, one end of which is arranged preferably at the base of the element 33 to pass over a suitable pulley 86 supported by means of a bracket 87 extending from the casing 46. This bracket 87 may also serve as a shield and is located adjacent to and extends over the gear 48. Another pulley 88 is provided and over which the endless conveyer 85 passes. This pulley 88 is supported preferably by means of brackets 89 connected with the support 15, and the endless conveyer is preferably inclined, although it may be arranged at any desired angle with respect

to the bottom of the tunnel. Thus, it will be seen that the material delivered thereon will be conveyed to a point in the rear of the machine.

5 Motion may be imparted to the conveyer in any suitable manner, but preferably from the motor 40 through the medium of the shaft 38, and to that end, there is provided on the shaft 38 a sprocket gear 90 (see particularly Figs. 2 and 3) over which a sprocket chain 91 passes, and this sprocket chain also passes over a sprocket gear 92 on a stub shaft 93 and to which shaft is connected a beveled gear 94, which meshes with another beveled gear 95, and which latter gear is connected with a shaft 96 of the pulley 88, and over which pulley the endless conveyer 85 passes. In order that the material may be delivered to the conveyer 85, one end of 10 the conveyer extends beneath the housing 56, and which latter is provided with a suitable opening therethrough above the conveyer, and the wall of the housing extends downwardly and projects over the edges of 15 the conveyer 85 as at 97 (see particularly Figs. 3 and 7).

To permit the ready removal of the cutter heads 58, the yokes 67 may, if desired, be of a sectional construction.

20 30 It is thought that the operation of this machine will be clearly understood from the foregoing description, but, briefly stated, it is as follows:

The machine is started to operate by 35 means of the motor 40, the motion of which is transmitted to the shaft 38. This motion is in turn transmitted to the disk or element 33 to rotate the latter, which imparts a bodily rotary motion to the cutters 40 about the shaft 32 as an axis, and as the scoops 82 are also supported by the disk or element 33, they will be given similar rotation.

The motion of the shaft 38 is also transmitted through the medium of the sprocket chain 91 and the associated gearing to the endless conveyer 85. As the disk or element 33 rotates, and as the material is cut away by the cutters, the latter being given a rotary movement with respect to the supporting disk or element 33 through the medium of the motor 72, the machine will be slowly advanced through the medium of the worm gear connection 47-48 (see Fig. 13). This 45 is accomplished by means of the rollers 51 which are connected with the gear 48 through suitable gear connections, and as they contact with the wall of the tunnel, it will be seen that as the rollers continue to 50 rotate, the forward part of the machine will advance. The supporting structure 15-21 being connected with the forward part of the machine through the medium of the connecting rods 54, it will be seen 60 that the forward part will draw the rear

part along with it. The cut away material and muck gathered by the scoops as they are rotated will be delivered to the conveyer 85, by means of which latter the material will be conveyed to the rear of the 70 machine or to any desired point out of the way of the operator and of the machine.

As the work progresses, the breast of the tunnel will be completely broken down, owing to the fact that the cutters are so 75 arranged with respect to each other as to avoid the formation of ribs, and the cutters operating at a high speed will remove the material without unnecessarily jarring the machine, and the cutters will operate uniformly throughout the entire area of the breast of the tunnel.

The principle of operation of this machine is to actuate the cutters with great rapidity, thereby removing the particles of 85 rock with less strain on the tool and machine.

When it is desired to change the course of the tunnel, the forward part of the machine, which is connected with the support 21, is 90 shifted by means of the connecting members 21^a, by means of the operating handle or wheel 30, which, through the medium of the gears 28-29-27-26 and rack 25 will cause the forward part of the machine to 95 have a pivotal movement with respect to the support 15, and the latter will be maintained against movement by means of the rollers 16. When it is desired to change the course of the tunnel by raising or lowering the course, this may be accomplished by adjusting the wheels 19 so as to vary the position of the support 15 by raising or lowering it with respect to the rollers 16. This latter action will have the effect of 100 causing the forward end of the machine or cutters to change their course in a vertical direction.

105 What is claimed as new is:—

1. A tunneling machine embodying a rotatable support, means for rotating the support, cutters mounted upon the support for rotation therewith and for independent rotation with respect thereto, means for imparting such independent rotation to the 115 cutters, and means responsive to the movement of said support for advancing the cutters.

2. A tunneling machine embodying a rotatable support, means for rotating the support, cutters mounted upon the support for rotation therewith and for independent rotation with respect thereto, means for imparting such independent rotation to the 120 cutters, and means responsive to the rotation 125 of the said support for advancing the cutters, the last recited means embodying mechanism engaging the wall of the tunnel.

3. A tunneling machine embodying a rotatable support, means for continuously ro- 130

tating the support, cutters mounted upon the support for rotation therewith and for independent rotation with respect thereto on axes disposed at an angle to the axis of rotation of the support, actuating means for imparting a continuous and independent rotation to the cutters with respect to the said support, and means responsive to the movement of the support for advancing the cutters.

4. A tunneling machine embodying a rotatable support, means for rotating the support, a plurality of cutters mounted upon the support for bodily rotation therewith and for independent rotation with respect thereto, actuating means operating directly upon the cutters for imparting such independent rotation to the cutters, the axis of rotation of the cutters being disposed at an angle to the axis of rotation of the said support and means responsive to the movement of the support for imparting a continuous advancing movement to the cutters.

5. A tunneling machine embodying a rotatable support, a plurality of cutter elements mounted upon the support for rotation therewith and for independent rotation with respect thereto on axes inclined to the axis of rotation of the support, actuating means operating directly upon the cutters for imparting such movements to the cutters, means for gathering up and conveying away the material as it is cut, the last recited means embodying a scoop connected with and rotatable with the said support, and means responsive in its operation to the rotation of the said support for advancing the machine.

6. A tunneling machine embodying a rotatable support, means for continuously rotating the support, cutters mounted upon the support for rotation therewith and for independent rotation with respect thereto, means for imparting a continuous and independent rotation to the cutters with respect to the said support, and means responsive in its operation to the rotation of the support for continuously advancing the cutters.

7. A tunneling machine embodying a rotatable support, means for continuously rotating the support, cutters mounted upon the support for rotation therewith and for independent rotation with respect thereto, means for imparting a continuous and independent rotation to the cutters with respect to the said support, and means responsive in its operation to the rotation of the support for continuously advancing the machine, the last recited means embodying mechanism engaging the wall of the tunnel and movable thereover.

8. A tunneling machine embodying a rotatable support, means for continuously rotating the support, cutters mounted upon the support for rotation therewith and for

independent rotation with respect thereto, means for imparting a continuous and independent rotation to the cutters with respect to the said support, and means responsive in its operation to the rotation of the support for continuously advancing the machine, the last recited means embodying mechanism engaging the wall of the tunnel and movable thereover and having a worm gear connection with the said support.

9. A tunneling machine embodying a rotatable support, a plurality of cutter elements mounted upon the support for rotation therewith and for independent rotation with respect thereto, a second support disposed in rear of the first said support, mechanisms mounted upon the second said support for imparting rotation to the first recited support and the said independent rotation to the said cutters, means connecting the supports for simultaneous advancement, and means responsive to the rotation of the first recited support and embodying mechanism engaging the tunnel wall for advancing the supports.

10. A tunneling machine embodying a rotatable support, a plurality of cutter elements mounted upon the support for rotation therewith and for independent rotation with respect thereto, a second support disposed in rear of the first said support, mechanisms mounted upon the second said support for imparting rotation to the first recited support and the said independent rotation to the said cutters, means connecting the supports for simultaneous advancement, means responsive to the rotation of the first recited support and embodying mechanism engaging the tunnel wall for advancing the supports, the second said support embodying elements shiftable with relation to each other for changing the course of the tunnel, and means for shifting the last recited elements one with relation to the other.

11. A tunneling machine embodying a rotatable support, a plurality of cutter elements mounted upon the support for rotation therewith and for independent rotation with respect thereto, a second support disposed in rear of the first said support, mechanisms mounted upon the second said support for imparting rotation to the first recited support and the said independent rotation to the said cutters, means connecting the supports for simultaneous advancement, means responsive to the rotation of the first recited support and embodying mechanism engaging the tunnel wall for advancing the supports, and means for raising and lowering the second recited support with relation to the first recited support.

12. A tunneling machine embodying a rotatable disk-like support, means for rotating the same, a plurality of cutter elements mounted upon the support for rotation

- therewith and with respect thereto, rollers connected with the support for advancing the machine, and a worm gear connection between the disk and the said rollers for operating the latter when the disk is rotated.
13. A tunneling machine embodying a rotatable disk-like support, means for rotating the same, a plurality of cutter elements mounted upon the support for rotation therewith and with respect thereto, rollers connected with the support for advancing the machine, a worm gear connection between the disk and the said rollers for operating the latter when the disk is rotated, a
- 10 housing for the disk, and rollers disposed between the said housing and the periphery of the disk and upon which last recited rollers the said disk rests.
14. A tunneling machine embodying a rotatable disk-like support, means for rotating the same, a plurality of cutter elements mounted upon the support for rotation therewith and with respect thereto, rollers connected with the support for advancing the machine, a worm gear connection between the disk and the said rollers for operating the latter when the disk is rotated, said disk having an opening therethrough, and a scoop connected with the disk for rotation therewith, said scoop having communication with the said opening to discharge the cut material therethrough.
15. A tunneling machine embodying a rotatable disk-like support, means for rotating the same, a plurality of tubular members extending therethrough, cutter elements supported by the tubular members for bodily rotation with the disk and for independent rotation with respect thereto, a drum, endless belts extending through the tubular members and connecting the drum with the cutter elements, and means for rotating the drum to impart an independent rotation to the cutter elements with respect to the said disk-like support during the rotation of the latter.
16. A tunneling machine embodying a rotatable disk-like support, means for rotating the same, a plurality of tubular members extending therethrough, cutter elements supported by the tubular members for bodily rotation with the disk and for independent rotation with respect thereto, a drum, endless belts extending through the tubular members and connecting the drum with the cutter elements, means for rotating the drum to impart an independent rotation to the cutter elements with respect to the said disk-like support during the rotation of the latter, and means operatively connected with

the said disk-like support for advancing the machine.

17. A tunneling machine embodying a rotatable disk-like support, means for rotating the same, a plurality of tubular members extending therethrough, cutter elements supported by the tubular members for bodily rotation with the disk and for independent rotation with respect thereto, a drum, endless belts extending through the tubular members and connecting the drum with the cutter elements, means for rotating the drum to impart an independent rotation to the cutter elements with respect to the said disk-like support during the rotation of the latter, and means operatively connected with the periphery of the said disk-like support and operating to continuously advance the machine.

18. A tunneling machine embodying a rotatable disk-like support, means for rotating the same, a plurality of tubular members extending therethrough, cutter elements supported by the tubular members for bodily rotation with the disk and for independent rotation with respect thereto, a drum, endless belts extending through the tubular members and connecting the drum with the cutter elements, means for rotating the drum to impart an independent rotation to the cutter elements with respect to the said disk-like support during the rotation of the latter, and a conveyer operatively connected with the said disk operating means for gathering and conveying away the material as it is cut.

19. A tunneling machine embodying a rotatable disk-like support, means for rotating the same, a plurality of tubular members extending therethrough, cutters supported by the tubular members for bodily rotation with the disk and for independent rotation with respect thereto, a drum, endless belts extending through the tubular members and connecting the drum with the cutter elements, means for rotating the drum to impart an independent rotation to the cutter elements with respect to the said disk-like support during the rotation of the latter, a conveyer responsive in its operation to the actuation of the said disk operating means for conveying away the material, and a scoop connected with the said disk for gathering and delivering the material to the said conveyer.

In testimony whereof I have signed my name to this specification on this 13th day of July, A. D. 1918.

C. W. HODGSON.
